C. E. BURKE.
ADJUSTABLE CLAMPING DEVICE,
FILED FEB. 2, 1922.

Inventor

Clarence E. Burke.

By Harry DeWallace

Attorney

UNITED STATES PATENT OFFICE.

CLARENCE E. BURKE, OF SYRACUSE, NEW YORK.

ADJUSTABLE CLAMPING DEVICE.

Application filed February 2, 1922. Serial No. 533,579.

To all whom it may concern:

Be it known that I, CLARENCE E. BURKE, a citizen of the United States, residing at Syracuse, in the county of Onondaga and 5 State of New York, have invented certain new and useful Improvements in Adjustable Clamping Devices, of which the following is a specification.

This invention relates to adjustable means 10 for assisting in assembling and temporarily holding the flexible bands which surround the transmission drums of Ford automobiles, while the covers of the transmission casings are being either applied or removed.

15 The object of the invention is to provide a novel, simple and handy clamping device for transmission bands comprising similar arms which are arranged parallel to each other and which may be adjusted for regulating the spacing of the said arms for aligning, drawing together, and holding the 20 ends of the bands in substantial registry, while other parts are being applied. A further object is to provide novel adjustable 25 means for connecting the said arms, said means comprising a rod carried by one arm which is telescopically received by a tube carried by the other arm, and a sleeve-nut which is slidable on said rod and engages 30 the threaded split end of the tube, by means of which the tube may be solidly clamped to the rod for holding the arms in different 35 adjusted positions.

I attain these objects by the means set 40 forth in the detailed description which follows and as illustrated by the accompanying drawing, in which—

Figure 1 is a top view of a portion of the transmission mechanism including the transmission drums and the corresponding bands, to which my clamping device is applied. Fig. 2 is an enlarged plan view and partial section of the clamping device; showing by full and dotted lines the adjustable nature 45 of the same. Fig. 3 is an end view of the clamping device. Fig. 4 is a sectional view taken on line 4—4 of Fig. 2. And Fig. 5 is a view of the split end of the connecting tube.

50 In the drawing 2, 3 and 4 represent respectively the reverse, low speed, and brake drums of the transmission assembly. These drums are usually surrounded by more or less flexible bands 2', 3' and 4', which are split 55 and their ends are provided with radial

lug 2^a, 3^a and 4^a which are normally spaced a considerable distance apart for facilitating adjustment while the transmission mechanism is in the operative condition. These bands are frequently relaxed and tightened 60 up, and when they become worn to a certain extent the old bands are removed and new bands are installed. In order to perform this exchange of the bands, the cover of the transmission case (not shown) must 65 be removed, and when the new bands are replaced on the drums, it is necessary to use some form of clamp, which is usually applied to the extended lugs 2^a, 3^a, 4^a, in order to hold them in the proper position relatively to the drums until the cover is replaced. The present invention has for its 70 object to provide a novel and simple clamp, which will now be described: 5 and 5' represent similar straight arms, preferably made 75 of steel of any suitable cross-section, and of equal length. The corresponding ends of said arms are perforated, as at 5^a to receive rods 6 and 6', which are preferably round and are driven tightly into the perforations 80 of the arms. The arms 5—5' are intended to be disposed and held substantially parallel to each other, and they are also preferably adjustable towards and away from each other, so as to vary their spacing, for facilitating the clamping and gaging of band-lugs of different spacings. To this end the rods 6 and 6' are of different lengths, and their combined length is intended to be less 85 than the normal spacing of the two arms. 90 The rod 6 is preferably the shortest, and is employed for supporting a relatively long tube 7, which is rigidly mounted on the short rod, with one end in contact with the arm 5. The opposite end of the tube 5 95 is threaded externally and this end is also split as shown at 6^a, for facilitating the contraction and expansion of the said end. The rod 6' is preferably of considerable length and slidably telescopes the split-end of the 100 tube 7, for affording the aforesaid adjustment of the arms 5 and 5' towards and from each other. In order to hold the arms of the clamp in the different adjusted positions, as shown by the full and dotted lines 105 in Fig. 2, I provide a sleeve-nut 8 having a plain tubular portion 8', which slidably fits the rod 6', and adjacent the said portion the nut is expanded, as at 8^a, and is internally threaded for screwing on to the 110

split-end of the tube 7. By this construction and arrangement, as the nut 8 is screwed on to the tube, the split-end of the latter is contracted sufficiently to effect a tight grip on 5 the rod 6'. The enlarged portion 8^a of the nut is preferably knurled, as at 8^b, for rendering the operator's grip more effective when tightening and loosening the nut.

Having thus described my invention, what 10 I claim, is—

1. A clamping device comprising similar arms of equal length, the corresponding ends of said arms being perforated, rods of unequal length driven into the perforations of 15 the arms and extending at right angles thereto, a tube rigidly mounted on the shortest rod and slideable on the longer rod and having its free end externally threaded and split, and a sleeve-nut slideable on the longer 20 rod adapted when screwed on to the tube

to contract its split end for rigidly holding said arms in various adjusted positions.

2. A clamping device including similar arms of equal length, the corresponding ends of said arms being perforated, rods driven 25 into the perforations of said arms and extending at right angles from the facing sides of the arms, a tube telescoping said rods for holding said arms parallel to each other, said tube being rigid on one rod and 30 slideable on the other rod, the free end of said tube being externally threaded and the threaded portion thereof being split longitudinally, and a nut slideable on one of said rods adapted to engage the split end of the 35 tube for holding said arms in a number of adjusted positions.

In testimony whereof I affix my signature.

CLARENCE E. BURKE.
